CLAIM

I claim the ornamental design for a bag holder, as shown and described.

DESCRIPTION

FIG. 1 is a front perspective view of the bag holder of the present invention;

FIG. 2 is an elevational view of the horizontal element of the bag holder, the vertical element not shown for convenience of illustration;

FIG. 3 is an elevational view of the vertical element of the bag holder, the horizontal element not shown for convenience of illustration; and,

FIG. 4 is a front perspective view of the bag holder of FIG. 1, shown holding a bag in broken lines which forms no part of the claimed design.
